[57] CLAIM

The ornamental design for a lapel microphone, as shown and described.

DESCRIPTION

FIG. 1 illustrates a top perspective view of the lapel microphone;

FIG. 2 illustrates a bottom perspective view of the lapel microphone;

FIG. 3 illustrates a left side view of the lapel microphone;

FIG. 4 illustrates a top view of the lapel microphone;

FIG. 5 illustrates a front side view of the lapel microphone;

FIG. 6 illustrates a right side view of the lapel microphone;

FIG. 7 illustrates a back side view of the lapel microphone; and,

FIG. 8 illustrates a bottom view of the lapel microphone.

The broken line showing of the clip on FIGS. 1 and 2, is for illustrative purposes only and forms no part of the claimed design.
